FIG. 2

UNITED STATES PATENT OFFICE

2,178,389

HUMIDIFYING APPARATUS

Stephen Bentley, St. Lambert, Quebec, Canada

Application June 9, 1937, Serial No. 147,298

1 Claim. (Cl. 237—78)

This invention relates to humidifying apparatus in which steam, derived from the steam line or radiator of a steam heating system, is used as a humidifying agent.

More particularly, the apparatus provided in accordance with this invention comprises a pair of steam coils housed in a condensate collecting chamber and having their inlet ends connected to a steam line or radiator to receive steam therefrom. The steam, after traversing the two coils, passes to the upper portion of the condensate collecting chamber from whence it escapes to the atmosphere through a suitable outlet at the top of said chamber.

Proceeding now to a more detailed description reference will be had to the accompanying drawings which—

Fig. 1 is a vertical sectional view of the humidifying apparatus provided in accordance with this invention.

Fig. 2 is a view similar to Fig. 1 but showing a slight modification.

In the construction shown in Fig. 1 steam is passed from a steam line or radiator 5 through a valve 6 to the intake ends of a pair of steam coils 7 and 8. These coils are housed in a condensate collecting chamber 9 provided with a top steam outlet 10 and a bottom condensate outlet 11. The discharge ends of the coils are directed downwardly so that the escaping steam impinges against the heated convolutions of the coils and then rises toward the outlet 10. The condensate collecting chamber comprises a body portion 12 and a base portion 13 which are screwed together as indicated at 14 so that they may be easily separated to give access to the coils 7 and 8. The body portion 12 of the condensate collecting chamber is formed to provide a tubular neck 15 which surrounds the outlet 10 and terminates in a cup-like portion 16. Condensate, separating from the steam as it leaves the outlet 10, is caught in the cup-like portion 16 and drops back through the outlet.

A float valve 18 is mounted on the support 19 in the upper portion of the chamber 9 and is adapted to close the outlet 10 when the chamber is flooded by condensate due to failure of the heating system.

The valve 6 comprises a valve casing 20 equipped with a rotary plug valve 21 which is opened or closed by means of a suitable handle 22. One end of the valve casing 20 is tapped into the steam line or radiator 5 and provided with a deflector 23 by which steam is deflected into the steam passage 24 of the valve. The other end of

the valve casing 20 is threaded onto a tubular extension 25 formed integral with the base 13 of the chamber 9. The inlet ends of coils 7 and 8 are soldered in place within the tubular extension 25 so that the coils constitute the only means of conducting steam from the valve casing 20 to the interior of chamber 9. The condensate escaping through the bottom outlet 11 of the chamber 9 passes into a suitable return conduit 26, the lower end 27 of which is adapted to be connected to the return line of the steam heating system. A check valve 28 is arranged in the conduit 26 to close the same in the event of back pressure.

If desired a suitable trap may be connected between the coils 7 and 8 and the steam supply 5 for the purpose of removing as much water as possible from the steam before it enters the coils. Such a modification is shown in Fig. 2 in which 30 designates a vertically disposed trap chamber interposed between the valve 6 and the steam line or radiator 5. As here shown the chamber 30 comprises a cylindrical body portion 31 provided with removable top and bottom caps 32 and 33 in threaded engagement therewith. Steam is supplied to said chamber through a steam inlet 34 which is tapped into the cylindrical body portion 31 at a point substantially midway between its ends. A baffle 35 is arranged at the inner end of the inlet 34 to direct the incoming steam toward the bottom of the trap chamber. The top cap 32 of the trap member is provided with a steam outlet opening 37 which is threaded to receive one end of the valve casing 20. Condensate escapes from the trap chamber 30 through a bottom outlet 38 and passes into a suitable return conduit 39 which connects with the previously mentioned return conduit 26 at a suitable point as indicated at 40.

A suitable screen 41 is preferably arranged over the bottom outlet 11 of chamber 9 to prevent clogging of the outlet 26 by foreign matter entrained by the steam entering said chamber.

Having thus described what I now consider to be the preferred embodiment of this invention it will be understood that various modifications may be resorted to within the scope and spirit of the appended claim.

I claim:

Humidifying apparatus comprising a casing provided with a top opening for the escape of steam, a bottom opening for the escape of condensate and a side opening surrounded by a coupling nipple adapted to be connected to a source of steam, said top opening being surrounded by 55

an upwardly projecting neck having its upper end enlarged to provide a condensate collecting cup, a vertical steam coil arranged in said casing, said coil being open at both ends and having its lower end secured in said coupling nipple so that steam supplied to the latter is permitted to enter the casing only through said coil, a float support

arranged in the casing at a point located above the coil but at a substantial distance below said top opening and a movable float on said support adapted to close off the top opening when the casing is flooded.

STEPHEN BENTLEY.
